CUSHIONING DEVICE

Charles W. Greenhill, New York, N. Y.

Application February 8, 1935, Serial No. 5,526

1 Claim. (Cl. 155—179)

This invention relates to cushioning devices such as seat pads and the like articles, and methods of making the same.

An object of this invention is to provide a cushioning device of the character described, having a plurality of air cells and a highly improved and economical method for providing such air cells.

A further object of this invention is to provide a chair pad of the character described, so constructed as to provide ample support and having a channel therein to minimize perspiration and permit circulation of air.

A still further object of this invention is to provide an improved and durable cushioning device of the character described, which shall be comparatively inexpensive to manufacture, comfortable in use, and withal practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claim.

In the accompanying drawing, in which is shown one of the various possible illustrative embodiments of this invention,

Fig. 1 is a top plan view of a chair pad illustrating a cushioning device made in accordance with my invention, with parts in cross-section to show the interior construction;

Fig. 2 is a cross-sectional view taken on line 2—2 of Fig. 1;

Fig. 3 is a cross-sectional view taken on line 3—3 of Fig. 1;

Fig. 4 is a perspective view illustrating the construction of the core used in making one of the air cells;

Fig. 5 is a partial, perspective view of another core used in making the air cell;

Fig. 6 is a top plan view of an air cell made 45 from the core shown in Fig. 4 with part broken away; and

Fig. 7 is a top plan view of an air cell section made in accordance with my invention.

Referring now in detail to the drawing, 10 50 designates a cushioning device embodying the invention, here shown for the purpose of illustration in the form of a chair or seat pad. The pad comprises a sheet 11 of cardboard or the like stiff material. Mounted on the cardboard 11 are a pair of air cell sections 12, hereinafter

described in greater detail. The sections 12 are preferably placed on the cardboard in diverging relation to one another for a purpose presently to appear.

Disposed about the sections 12 are masses or layers 14 of cotton, felt or other soft material, covering the top, sides and ends of said sections. Covering the cardboard 11 and the masses 14 is a seat cover 15 of felt, cloth, leatherette, velour or other suitable covering material. The covering 15 has a bottom portion 16 contacting the underside of the cardboard 11, portions 17 and 18 covering the two separate layers 14 which are disposed about the two sections 12, and a portion 19 contacting the top of the cardboard 11 and forming a triangle at the longitudinal mid-section of the pad, and separating the two diverging cushioning portions thereof. A channel 20 is thus formed between the two sides of the chair pad, for air circulation to provide comfort for the occupant.

The sections 12 are similar and each comprises a bottom wall 25, a top wall 26 preferably parallel to the bottom wall, downwardly and outwardly diverging end walls 28, downwardly and outwardly diverging side walls 29, and a plurality of downwardly and inwardly converging partitions 30 dividing said section into a plurality of air spaces or pockets 31. The sections 12 may be made of any suitable resilient material such as a latex composition, preferably one which may readily dry without requiring any vulcanization and which is not tacky. The sections 12 may be made preferably in the following manner:

A plurality of cores or hollow bodies 35 are made from cardboard, paper, or other suitable sheet material. In Fig. 4 there is shown a core 35 made of sheet cardboard cut from a single blank and creased, folded and pasted into suitable shape. As shown in Fig. 4, the core 35 has a flat relatively wide bottom wall, a short and relatively narrow top wall, and downwardly and outwardly diverging side and end walls. The core 35 is completely enclosed and hollow.

In Fig. 5 there is shown another core 36 likewise made of cardboard and being completely enclosed and hollow but having a wider and shorter top wall 37 and a narrower and longer bottom wall 38. The core 36 has downwardly and outwardly diverging end walls 39 but inwardly and downwardly converging side walls 40.

Each section 12 may be made with two cores 35 between which there is interposed a complementary core 36. Preferably the cores 35 and 36

are first individually dipped in the latex composition; then placed together, as shown in Fig. 7, and again dipped together several times in the latex composition, and then allowed to dry, thus forming a section having three air spaces or pockets 31, the bottom and top walls 25 and 26, the side walls 29, end walls 28 and the partitions 30. The latex or rubber composition completely enclosing each of the cardboard hollow cores 35 and 36 retains the air within the cells, so that air cushions are thus formed. After some use the cardboard cores 35 and 36 will be crushed and crumple or break up within the spaces 31, the cores 35 and 36 merely serving as a mold for forming the latex or rubber cell.

It will be noted that by making the members 35 and 36 with inclined side and end walls no vertical walls are presented in the finished chair pad whereby the pad is comfortable in use before the cores are broken up. If desired the cores 35 and 36 may be placed together before the first dipping with the center core 36 spaced from the members 35 on opposite sides thereof by rubber cement or in any other suitable manner whereby spaces are left between the adjacent walls of said cores. The cores 35 and 36 thus attached together, may then be dipped in the latex composition one or more times to produce a casing of any desired thickness.

It will be noted that the two sections of the chair pad, looking at Fig. 1, are closer together adjacent the rear edge 40 of the pad and are further apart at the front edge 41 of the pad. The

two sides of the chair pad support the thighs and buttocks of the occupant and the channel 20 permits air to circulate, thereby reducing perspiration and adding to his comfort.

Although the drawing shows a chair pad embodying my invention, it will be understood that any other cushioning devices, for example, mattresses and the like articles, may be made with my improved air cells and in accordance with the method of making the air cells described

It will be also understood that life saving belts or other devices may be made with air cells constructed in the manner described hereinabove.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing, is to be interpreted as illustrative and not in a limiting sense.

Having thus described my invention, I claim as new and desire to secure by Letters Patent:

A multi-cell cushioning device comprising a section having a plurality of air pockets of substantially trapezoidal cross-section longitudinally and transversely arranged with one of said trapezoidal pockets adjacent an inverted trapezoidal pocket.

CHARLES W. GREENHILL.
